STEP SWITCHER FOR REGULATING
TRANSFORMERS

Bernhard Jansen, Regensburg, Germany

Application January 13, 1931, Serial No. 508,447,
and in Germany January 24, 1930

10 Claims. (Cl. 171—119)

The present invention relates to a switch regulation method by means of which the taps of a transformer can be changed while in normal uninterrupted use.

5 In a much used form of construction of such step-switches the transformer taps succeeding one another are arranged on a circular contact path and a double-pole switch which can be displaced by a crank is moved from one tap to the next one. The double-pole switch by means of which the changing-over from the tap in use to the tap above or below is effected is—besides possessing permanent contacts—generally provided with pre-contacts and bridge-resistances. These 15 establish the connection with the next tap before the preceding one is left.

As with these step-switch regulations the double-pole switch following the contact path moves along the circumference from one tap to the next one, it is necessary that between the 20 taps there should always be, in the direction of the circumference, the gaps needed for the switch-over. In the case of medium or large outputs this requires a great length of the contact path. 25 This circumstance is particularly annoying in the circular arrangement because the surface of the circle increases in square proportion to the circumference.

It is for this reason that with the step-switches 30 for medium and large outputs which are on the market at the present time the double-pole switch is arranged separately from the step-selector. This, however, necessitates complicated driving mechanisms and the serial connection of several 35 movable contacts, which gives rise to faulty working.

I have now found that it is possible to combine the double-pole switch with the step-selector, even in the case of medium and large outputs. To attain this end the transformer taps are distributed 40 upon the circumference of a circle in such a manner that from each tap the next tap above or below is reached on the chord of a circle of the largest possible length. In the maximum case this chord 45 equals the diameter of the circle. Thus the double-pole switch has now the entire length of the chord of the circle upon which to effect the switch-over, without the circumference having to be unusually large. For this reason also the 50 switch-over proper takes effect in the direction of the chord of the circle. In doing so the double-pole switch which is arranged upon a carriage can move either with the carriage or independently of it. The choice of the switch-over to the 55 next step above or below is effected by swinging

the carriage with the double-pole switch from one direction of the chord into the other around the tap in use as a centre of rotation. If the chord, as in the maximum case, is the diameter of the circle, the swinging takes place around the 60 centre of the circle.

The two fundamental forms of the step-switch regulation are shown in the drawings in which

Fig. 1 is a front elevation of a step-switch arrangement for eight taps, with a tap cut in for 65 normal operation;

Fig. 2 is a plan view of the device of Fig. 1 in the position illustrated in Fig. 1;

Fig. 3 is a front elevation of the device of Fig. 1 showing the device in an intermediate position 70 during the cutting in of another tap;

Fig. 4 shows in plan the position of the device as in Fig. 3;

Fig. 5 shows the device of Fig. 1 in front elevation with a different tap cut in; 75

Fig. 6 illustrates in plan the position of the device as in Fig. 5;

Fig. 7 discloses in front elevation a device similar to that of the foregoing figures but embracing mechanism for effecting a very rapid shifting of 80 the switch from one tap to another;

Fig. 8 is a detail view of said mechanism;

Fig. 9 illustrates in front elevation a modification of the invention showing a tap cut in for normal operation; 85

Fig. 10 is a plan of the device in the position of Fig. 9;

Fig. 11 discloses an elevation of the device of Fig. 9 in an intermediate position it assumes in cutting in a tap; 90

Fig. 12 is a plan view of the position of the device in Fig. 11;

Fig. 13 is an elevation indicating a position of the device of the preceding figures in which two 95 taps are simultaneously cut in;

Fig. 14 shows in elevation a different tap cut in;

Fig. 15 is a plan of Fig. 14, and

Figs. 16 and 17 are respectively an elevation and plan showing the device in a position in which 100 a still different tap is cut in.

Figs. 1 to 7 represent a step-switch regulation for 8 taps in different working positions. The positions of the device in Figs. 1, 2, 5 and 6 are two permanent positions in which the main A is 105 connected with the transformer-tap 1 or 2, as the case may be. The transformer-taps 1-8 are held together by a supporting bracket R of regular star-octagon shape. The supporting bracket it- 110 self or any other supporting construction which

can take its place, is located across the potential of the main A. A crank B is fastened to the driving shaft H which shaft passes through the central axis H' of said bracket R. Said crank 5 serves to effect movement of the carriage C to which the double-pole switch D is firmly fastened. In both ends of the carriage C there are slots T by means of which the carriage can engage the cylindrical holders N of the taps and thus 10 guide itself. With a turn of the crank B the carriage C therefore describes a shifting movement in the direction of its own longitudinal axis combined with a swinging movement first around the axis of the tap 1 and then around the axis of the 15 tap 2, until the position of Figs. 5 and 6 has been reached. The positions of the carriage which run radially from the centre of the circle to the tap in use for the time being have to be considered as permanent working positions. At the same 20 time the crank B is then in its greatest stretching position so that, with the aid of the double-pole switch D, it can exercise a great contact pressure upon the tap cut in. The double-pole switch D has the two-fold function of establishing in the 25 working positions illustrated in Figs. 1, 2 and 5 and 6 respectively a firm connection between the taps 1 and 2 respectively and the main A, by means of the contacts E₁ and E₂ respectively, and of maintaining the connection in the middle or 30 switch-over position of Figs. 3 and 4, after the main contacts E₁ and E₂ have been disconnected from the taps, by way of the resistances G₁ and G₂, aided by the pre-contacts F₁ and F₂.

In the middle or switch-over position the main 35 A is momentarily connected with both taps 1 and 2 at the same time, by way of the resistances G₁ and G₂. Here with a short-circuit current which is reduced to the desired value by the serially connected resistances G₁ and G₂ flows from the higher 40 tap to the lower one. Nevertheless the double-pole switch must not remain too long in this middle position as, generally speaking, the resistances will not stand a long cutting-in time. When, for 45 instance, the double-pole switch D is moved from the middle position into the end position of Figs. 5 and 6 the pre-contact F₁ interrupts the short-circuit and the main-contact E₂ soon after bridges over the resistance G₂ by establishing a direct connection of the tap 2 with the main A.

50 In order to spare the resistances G as much as possible the movement of the double-pole switch D from the radial position of Figs. 1 and 2 into the radial position of Figs. 5 and 6 should be effected in as little time as possible. This is 55 achieved by a quick movement of the crank B by virtue of the mechanism, shown in the drawings in Figs. 7 and 8. As will be seen from said figure, the carriage C is locked against rotation by means of a latch M located centrally in the 60 shaft S and projecting when in locking position into an opening M' in said carriage. Located on shaft S, below the crank B, is a second crank V, said crank having at its free end a downwardly projecting pin V'. A trip N₃ for the latch M is 65 pivoted on said crank V. A second shaft H is positioned below shaft S and has at its upper end a fitting W provided with three spaced arms N₁, N₂ and N₄. The arm N₄ has a depending pin N₅ secured thereto, said pin being connected by 70 means of a spring J with the depending pin V' of the crank V. The other arms N₁ and N₂ are provided with upwardly projecting teats.

75 This mechanism effects instantaneous movement of the double-pole switch D in the following manner. Upon rotation of the shaft H the

spring J is placed under tension but this force is ineffective to move the crank B due to the latch M. However, when the shaft H has been rotated sufficiently to bring the arms N₁ or N₂ under the trip N₃, the teat on said arm strikes the trip N₃, releasing the latch M. The force applied to the spring J thereupon acts to effect an instantaneous movement of the carriage C.

In the embodiment of the invention of Figs. 9 to 17 inclusive, the carriage C is also swung from the radial operating position (Figs. 9 and 10) to the chord position (Figs. 11 and 12) by turning the crank B, and the switch D moves with it, but carriage C remains stationary in the chord position while the switch makes an independent movement for establishing contact with the selected tap, i. e. tap 2. For this purpose it is composed of two separate switches K₁ and K₂, equipped with main contacts E₁ and E₂ and pre-contacts F₁ and F₂ connected by a connector L.

In the working-position shown in Figs. 9 and 10 the connector L and the switch K₂ form a stretched angle-lever by means of which the switch K₁ is firmly locked. Thus the main A is firmly connected with the tap 1 by way of the main contact E₁. The counter-position of Figs. 14 and 15 which relates to the tap 2 is reached when the connector L together with the switch K₁ hold the switch K₂ and its main contact E₂ locked. In order to come into the position illustrated in Figs. 14 and 15 from the position illustrated in Figs. 9 and 10 it is, however, necessary to let a shifting force act upon the connector in the direction of the tap 2. This is done by the force-spring J which is stretched by the crank B. There is, however, still a release necessary of the locking of the switch K₁ which had been effected by the stretched angle-lever. This is also performed by the crank B which, after complete tension of the spring J strikes against the switch K₂ and thereby opens the angle-lever.

Fig. 13 again shows the moment when the main A is connected simultaneously with both taps 1 and 2 by way of the precontacts F₁ and F₂ as well as the resistances G₁ and G₂; only in this form of arrangement the resistances G₁ and G₂ are not located on the double-pole switch but are in direct connection with each tap. This construction can, however, also be arranged in such a manner that the resistances are permanently connected with the double-pole switch.

The foregoing description shows the process of the switch-over of the main from tap 1 to tap 2 to be as follows:

Starting from the position shown in Figs. 9 and 10, the crank B is rotated to move the carriage C into the position illustrated in Figs. 11 and 12. Leaving the carriage in this position, the crank continues to rotate so as to extend the spring J. A roller on the crank then strikes the switch arm K₂ flexing the joint between said arm and link L and the extended spring J rocks the switch arms through the position shown in Fig. 13 to that of Figs. 14 and 15. The continued rotation of the crank then swings the carriage into the position shown in Figs. 14 and 15.

If now it is intended to switch over further to tap 3 the carriage C together with the double-pole switch D must be swung into the direction of the chord leading from 2 to 3 until the position of Figs. 16 and 17 is reached. This is effected by an additional turn of crank B, the centre of rotation being tap 2 which is in use at the time. Thereupon the crank B through further movement again stretches the spring J and after reach-

ing its end position carries the double-pole switch to tap 3 to effect an instantaneous switching-over.

A switching in opposite direction from 3 to 2 to 1 is attained by simple reversal of the turning 5 movement of crank B.

As has already been stated the uninterrupted switch-over e. g. from tap 1 to tap 2 is effected by leaving, after release of the main contact E₁, the main A connected for an instant with tap 1 by 10 way of the pre-contact F₁ and resistance G₂. In the middle position this path of the current is replaced by another path of current by way of the pre-contact F₂ and the resistance G₂ to the tap 2 for so long a time until the main contact E₂ can 15 take over the direct path of current. The change of the paths of current in the middle position takes place through momentary parallel circuiting of the second and the subsequent opening of the first path of current. The duration of the parallel 20 circuiting during which a stress is placed upon the resistances G₁ and G₂ not only by the working current but also by the short-circuit current flowing from the lower to the higher tap, as has already been stated, should be reduced to a minimum. This is done by making the two pre-contacts 25 F₁ and F₂ dependent on each other in their movement by gear-sectors X and X' as shown in Figs. 1 to 7 or by a coupling lever as shown in Figs. 9 et seq. The pre-contacts are equipped with 30 springs Y which cause them to open up as widely as possible. Their opening movement is then limited by one of the two pre-contacts F₁ or F₂ striking against the corresponding tap 1 or 2. Through 35 the inter-dependence of the two pre-contacts on another it is only possible in a single position (the middle position shown in Figs. 3, 4 and 13) for the two pre-contacts to touch the taps at the same time. However, since the middle position of the double-pole switch D is maintained for only a 40 moment, the cutting in time of both resistances G₁ and G₂ will be equally limited. Practically, therefore, they are stressed only by the working current and not by the short-circuit current that flows between the higher and the lower taps.

45 The driving of the step-switch regulations can be done by hand or by a motor in such a way that all three phases of a three-phase transformer cut in at the same time or that the phases cut in one after another whereby a triple number of steps is 50 obtained.

In general the step-switch regulation is arranged as a separate unit in air or oil outside the transformer. In many cases it can be built (see Fig. 11) directly on to the transformer-duct. The latter is, in that case, preferably constructed as a 55 multiple duct through which all transformer taps pass to the step-switch regulation. If it is not desired to lead out all the taps the double-pole switch alone can be arranged outside and the remaining part of the step-switch can be put up inside the transformer. This is possible, as shown 60 in Fig. 13, by providing the carriage with two contacts which are movably connected with the two poles of the double-pole switch that pass through 65 the duct. In this case it is of advantage with the three-phase zero regulation to embrace three step-switches to one whole. The three step-switches and the three double-pole switches are then put into motion by a single crank shaft which 70 passes through the duct. In this case, which relates to a three-phase transformer with earthed zero-point, the drive by motor can be done from the double-pole switch placed outside. The motor is connected with the zero-point potential and, 75 to prevent excess voltage, is fed by means of an

isolating transformer from the step-voltage of the regulation transformer or from some other source of energy.

What I claim is:

1. A step switch device for tapping in a transformer during use comprising a plurality of transformer taps arranged around the circumference of a circle, a movable carriage located between said taps, a double-pole switch connected to the electrical supply of the transformer and operably associated with said carriage and shifting means for moving the switch from a radial position for the normal connection of any of said taps to the main, to change to the next desired tap, first into registry with the chord between the functioning and selected taps and then into the radial position appropriate to the selected tap. 80

2. A device as claimed in claim 1 wherein the switch is mounted on said carriage. 90

3. A step switch device for tapping in a transformer during use comprising a plurality of transformer taps arranged around the circumference of a circle, a movable carriage located between said taps and having slotted ends for engaging said taps, a double-pole switch connected to the electrical supply of the transformer and secured to said carriage, a crank secured to said carriage and means for operating said crank to cause a shifting of said carriage whereby said switch is moved from a radial position for the normal connection of any of said taps to the main, to change to the next desired tap, first into registry with the chord between the functioning and selected taps and then into the radial position appropriate to the selected tap. 100

4. A step switch device for tapping in a transformer during use comprising a plurality of transformer taps arranged around the circumference of a circle, a movable carriage located between said taps and having slotted ends for engaging 105 said taps, a double-pole switch on said carriage and connected to the source of electrical supply of the transformer, said switch having means for making direct contact with said taps, and having

additional means for making momentary contact with said taps during movement of said carriage, a crank secured to said carriage and means for moving said crank to cause a shifting of said switch from a radial position for the normal connection of any of said taps to the main, to change 115 to the next desired tap, first into registry with the chord between the functioning and selected taps and then into the radial position appropriate to the selected tap, momentary contact between the tap cut out by movement of the switch 120 and that cut in by said movement being effected by said additional means. 125

5. A device as defined in claim 4 wherein the additional means for making momentary contact with the taps during movement of the carriage 130 comprise a plurality of arms pivoted to the switch and having contacts at their upper ends, meshing gear sectors at their lower ends and spring means for expanding the arms to cause the contacts thereon to strike the taps during movement of the switch. 135

6. A step switch device for tapping in a transformer during use comprising a plurality of transformer taps arranged around the circumference of a circle, a movable carriage located between said taps and having slotted ends for engaging 140 said taps, a double-pole switch connected to the source of supply of said transformer and secured to said carriage, a crank connected to said carriage, means for operating said crank 145

150

to cause a shifting movement of said carriage whereby said switch is moved from a radial position for the normal connection of any of said taps to the main, to change to the next desired tap, first into registry with the chord between the functioning and selected taps and then into the radial position appropriate to the selected tap and additional means cooperating with said crank to effect an instantaneous movement of the carriage.

10 7. A device as recited in claim 3 wherein means are provided to prevent but a momentary contact between the tap cut out by movement of the switch and that cut in by said movement.

15 8. A step switch device for tapping in a transformer during use comprising a bracket for supporting eight transformer taps around the circumference of a circle, a shaft journaled centrally in said bracket, a movable carriage located between said taps, said carriage having slotted ends for receiving said taps, a double-pole switch secured to said carriage and connected to the source of supply of said transformer, a plurality of contacts on said switch for making a direct con-

25

tact with said taps, a plurality of arcuate arms pivoted at their lower ends to said switch and having pre-contacts at their upper ends, resistance means connecting said switch and said pre-contacts, spring means for expanding said arcuate arms, a crank secured to said shaft and to said carriage for effecting a shifting movement of said carriage whereby said switch is moved from a radial position for the normal connection of any of said taps to the main, to change to the next desired tap, first into registry with the chord between the functioning and selected taps and then into the radial position appropriate to the selected tap, said pre-contacts making contact with the tap cut out by movement of said switch and the tap cut in by said movement, and means cooperating with said crank for rendering said last named contact instantaneous.

80 9. A device as recited in claim 1 wherein the switch is movable independent of said carriage.

10. A device as recited in claim 1 wherein said switch comprises a pair of levers connected by a link at their upper ends.
